TRANSFORMER APPARATUS

Lewis A. Medlar, Lansdale, Pa., assignor to Fox Products Company, Philadelphia, Pa., a corporation of Pennsylvania

Original application Mar. 15, 1957, Ser. No. 646,429, now Patent No. 2,999,973, dated Sept. 12, 1961. Divided and this application Aug. 21, 1961, Ser. No. 132,845
12 Claims. (Cl. 323—60)

This invention relates to a transformer system for supplying power from an A-C. input to a load, and, more particularly, to a transformer system for supplying a substantially constant current to a load subject to variations of impedance. This application is a division of my copending application Serial Number 646,429, filed March 15, 1957, and now U.S. Patent 2,999,973.

As will be understood after the following explanation, the transformer system of this invention is capable of supplying a large number of different characteristic outputs. Among such outputs are a characteristic rise of current output with increasing load, a characteristic drop of current output with increasing load, and a substantially constant current output with increasing load. The invention will be more fully described in conjunction with the last-mentioned characteristic, which is preferred, but it will be understood that the invention is not limited to this characteristic.

In the past, several different means of obtaining a substantially constant current output with changing load impedance have been evolved. Perhaps the earliest of these various systems is that using a movable coil, the coil being counter-balanced and automatically adjusted in accordance with changing load to vary the distance between the input and output sides of the transformer and thereby to vary the coupling. This system is still in use today for constant current lighting systems, but it is subject to several disadvantages, among which are poor speed of response, the substantial expense of the system, the bulkiness of the unit, and the use of moving parts subject to wear and eventual shutdown of the system.

Another past-suggested constant current apparatus uses a saturable core reactor. The reactor may be a relatively simple one or may be a complex system utilizing shunts, partial air gaps, etc. This type of system, however, is relatively expensive, as well as being complex. Moreover, it has a lagging power factor.

A third general type of known constant current system is one using a resonance phenomenon. This type of system has taken many forms, but the simplest form is the series resonant circuit, including an inductive reactance and a capacitive reactance connected in series, the two reactances being adjusted to be substantially equal, and the load being connected across one of the reactances. While this type of system provides quite good constancy of output current, it has been found necessary to provide auxiliary means to limit the voltages across the components on open circuit. Moreover, this type of system is not readily adjustable to change the level of output current which is to be maintained constant. In order to provide for such change, there must be a change in both the actual inductance and the actual capacity of the components.

Another adaptation of the resonant system is the so-called "monocyclic square." This system is subject to several of the disadvantages enumerated above for the simple series resonant system.

In contrast to all of the above previously suggested systems, the transformer system of the present invention provides a substantially constant current output at

2

high efficiency, with no moving parts, with no need for auxiliary units to limit component voltages on open circuit, with relatively easy adjustment of the parts to change the level of output current to be maintained constant, and for a substantially lower cost than many of the previous systems.

The transformer system of this invention is in the nature of a resonant phenomenon, but, as will be obvious from the theoretical analysis to follow, it is far from a simple resonant phenomenon. None of the various embodiments of the invention to be described uses a simple series resonant circuit, and all of the embodiments actually automatically adjust themselves to maintain a substantially resonant condition even with change of only one of the components, such as change in capacity. The system is not dependent for its operation upon leakage reactance or on saturation of the core or any of its components, and the system actually is *limited* and adversely affected in its operation by these ever-present effects.

One important advantage of the transformer system of this invention is the fact that it draws a leading power factor current from the input, rather than the lagging power factor usually obtained with a transformer system.

The apparatus of the present invention is capable of use wherever it is desired to draw a substantially constant current through a variable load, when a constant voltage input is provided. One instance of such use is in lighting systems.

The apparatus of the present invention, generally described, includes an input, an output, and a control electrical circuit, each of these circuits including at least one coil which may be wound on a transformer core. The coils of the input and output electrical circuits are so inductively related, wound and connected with respect to one another that two magnetic circuits, an input and an output, are formed. The magnetic circuits have two common portions, in one of which the magnetomotive forces generated by the input and output currents aid, and in the other of which the magnetomotive forces generated by these currents oppose. As a result, there is no direct coupling of power between the input circuit and the output circuit. The control electrical circuit includes a capacitor and is inductively coupled to one of the coils of the input and output circuits through one of the common portions of the magnetic circuits. Current through the control circuit generates a magnetomotive force which is opposite in phase and of greater magnitude than the output magnetomotive force in the common portion through which the coupling takes place. The control magnetomotive force in effect reverses the output magnetomotive force in said common portion of the magnetic circuit and hence couples power from the input to the output through the control electrical circuit.

The invention will now be described in conjunction with the accompanying drawings, showing preferred embodiments thereof.

In the drawings:

FIG. 1 is a schematic diagram of a transformer system in accordance with the invention;

FIG. 2 is an equivalent electrical circuit diagram for the system of FIG. 1;

FIG. 3 is a diagrammatic illustration of the magnetic circuits of the transformer system of this invention;

FIG. 4 is a schematic diagram of a transformer apparatus similar to that of FIG. 1 but with load connected across the terminals which are the input terminals in FIG. 1 and the input connected across the terminals which are the load terminals in FIG. 1;

FIG. 5 is a schematic diagram of a transformer apparatus in accordance with the invention illustrating the use of a control coil in the control electrical circuit and the various connections possible with this control coil;

FIG. 6 is a schematic diagram showing a device for varying the effective capacity in the control circuit;

FIG. 7 is a schematic diagram showing transformer coupling of the capacitor in the control circuit; and

FIG. 8 is a schematic diagram illustrating the use of a saturable transformer to vary the effective capacity of the capacitor in the control circuit.

$$I_o = \frac{-Ep \left[p^2 K \frac{M_3 M_1 + M_2 L_3}{L_1 L_3 - M_3^2} - \frac{M_3 - M_2}{L_1 L_3 - M_3^2} \right]}{Z \left[p^2 K + \frac{L_1}{L_1 L_3 - M_3^2} \right] + p^3 K \left[L_2 - M_2 \frac{L_3 M_2 + M_1 M_3}{L_1 L_3 - M_3^2} - M_1 \frac{L_1 M_1 + M_2 M_3}{L_1 L_3 - M_3^2} \right] + p \left[1 + 2 \frac{L_1 M_1 + M_2 M_3}{L_1 L_3 - M_3^2} + \frac{L_1 L_2 - M_2^2}{L_1 L_3 - M_3^2} \right]}$$

Referring now to the drawings in detail, it will be seen that all of the embodiments of the invention illustrated include a four-legged shell-type core 50 carrying at least three coils, two of the coils being connected in series, with the load connected across one of the third coil and the series combination of the first two coils, and the input being connected across the other of the third coil and the series combination of the first and second coils. A capacitor is connected in a control circuit inductively coupled to one of the first and second coils. The core may be formed of any appropriate material, but it will be preferable in most cases that a standard transformer iron core be used and that stampings be assembled together to form the usual transformer laminations. With such a structure, magnetic paths are formed between the two outer legs of the core and between the outer legs and the center legs. If a ferromagnetic core material is employed, as is preferred, the permeability of the paths will be high in comparison with air.

In the basic system of this invention, as shown in FIG. 1, coil L₁ is wound around inner legs 51 and 52 of the transformer, with each turn of the coil encircling both of the legs. Coil L₂ is wound on leg 51, and coil L₃ is wound on leg 52.

The input source of A.-C. voltage of constant magnitude 53 is connected across coil L₁, while a load 54 is connected across the series combination of coils L₂ and L₃. A capacitor K is connected directly across coil L₃.

The transformer core, in addition to inner legs 51 and 52, also has outer legs 55 and 56, no coil being wound on either of these legs. Outer leg 55 includes portion b-a-h-g of the core, inner leg 51 includes portion c-b-g-f, inner leg 52 portion d-c-f-e, and outer leg 56 portion d-e. The portions a-h, b-g, e-f, and d-e of the four legs are substantially parallel to each other.

It is not necessary that the legs of the core be coplanar, or parallel, as shown in the drawings, or that the core be free of air gaps. It is only necessary that magnetic paths be formed between all legs of the core. As a matter of fact, as indicated above, the core material may be non-ferromagnetic, or air, as long as the increased reluctance and leakage of such a core is not too important or is compensated for by proper selection of the other parameters of the system.

These connections provide an input electrical circuit including coil L₁ and its connections connected directly across input 53, an output electrical circuit including coils L₂ and L₃ and their connections connected directly across load 54, and a control electrical circuit including coil L₃ and capacitor K. Load 54 may be of any type, but if constancy of current is desired, it is preferred that the load be mostly resistive in character, and, for best constancy, it is preferred that the load should be substantially of unity power factor.

The equivalent electrical circuit for the apparatus of FIG. 1 is shown in FIG. 2, in which the voltage supplied to coil L₁ by the input 53 is shown as E_p, the current driven thereby through the primary is shown as I_p, the

control coil current is shown as I_L, the output current is shown as I_o, and the output or load impedance is Z. In this circuit the mutual inductance, or inductive coupling, between coils L₁ and L₂ is shown as M₁, between coils L₁ and L₃ is M₂, and between coils L₂ and L₃ is M₃.

Using $p = j\omega$, setting up mesh equations for the input, output and control circuits, assuming one:one turns ratios, neglecting ohmic resistance of coils, leakage reactance and core loss, and solving for the load current, we obtain the following equation:

$$p^2 K + \frac{L_1}{L_1 L_3 - M_3^2} = 0$$

It is evident that the above equation is relatively complicated and not susceptible of easy analysis, but it will be noted that the impedance value Z appears in only one term, that being in the denominator of the equation. For the load current I_o to be entirely independent of load, the multiplier of the impedance Z must be zero, so we obtain:

$$\omega \left[\frac{L_1 L_3 - M_3^2}{L_1} \right] = \frac{1}{\omega K}$$

This last equation is obviously the condition for pure constancy of the load, or output, current. Through simple arithmetical operations on the last equation, we obtain:

This last equation is obviously for a resonant system, but it also is obviously not a simple resonance equation. The transformer coils and connections of FIG. 1 form two magnetic circuits in the transformer core. The first magnetic circuit, as shown in FIG. 3, includes portions i-b-a-h-g-i and j-c-d-e-f-j. This circuit is that followed by flux driven by the primary magnetomotive force, as shown in FIG. 3, with F_p representing the primary MMF. The second magnetic circuit includes the portions i-b-c-j-f-g-i of the core material. This magnetic circuit is traversed by flux driven by the output magnetomotive force F_o. It will be seen that in portion b-g of the left inner leg, the input and output magnetomotive forces oppose, while in portion c-f of the right inner leg, the output and input magnetomotive forces aid. If no control circuit were employed, there would hence be no coupling of power between the input and the load because the voltages in the differentially wound coils would cancel each other. However, the control coil current generates a magnetomotive force F_L which is opposed to the magnetomotive force F_o in portion c-f of the right inner leg, and is of such a higher magnitude, that the resultant between the control and output magnetomotive forces in this leg is substantially reversed from F_o and reflects into the primary or input circuit. Consequently, power is coupled between the input and the load through the control electrical circuit.

In general, operation of the transformer apparatus above described is similar to that explained in detail in my copending application Serial Number 646,429, filed March 15, 1957, of which the present application is a division, and said copending application sets out in detail a vector analysis, and characteristic curves, applicable to the apparatus here described.

In contrast to the simple resonant circuit of the prior art, the current regulation which can be obtained with devices constructed in accordance with the invention is substantially the same for each preselected value of capacitance, and the system apparently automatically changes the mutual inductance between coils on different legs so as to adjust the apparent reluctance of the core and compensate for the changed capacity in the control circuit.

Referring now to FIG. 4, the load 54 can be connected directly across coil L₁, and the input 53 be connected across the series combination of coils L₂ and L₃. This connection of the system results in substantially the same operation obtained with the connections shown in FIG. 1.

Referring to FIG. 5, it is possible to use a separate coil for the control circuit, and such a coil is shown as L₄ in this figure. With the separate coil, the control voltage available to drive the capacitor may be increased to a higher level, and the control circuit may obtain its voltage from any appropriate source. For instance, as shown in FIG. 5, the series combination of control coil L₄ and the capacitor C may be connected across L₁, coil L₂, coil L₃, the series combination of coils L₂ and L₃, any other source of voltage, or those terminals may be shorted. Various different characteristics may be obtained through use of these different connections, but the constancy of output current will be good with any of them, being best in that range when the control current is substantially 90° out of phase with the primary voltage at zero load voltage.

The capacitor in the control circuit of FIG. 5 is identified as C, rather than as K in the preceding figures. This indicates use of an actual capacitor, while the letter K has been used to represent an effective capacity. The equations have also been derived for effective capacity K, but the effect of the control coil can be taken into account in the equations by inserting for K the term $\beta^2 C$, where $\beta = 1 + \alpha$, and α is the turns ratio between load coil L₃ and control coil L₄.

For commercial use, it will be advantageous to provide for adjustment of the level of the output current which is to be maintained constant with the various embodiments of this invention. Such adjustment may be obtained by varying the capacity of the capacitor, but, especially at voltages of the magnitude used with a transformer system of this type, it will be preferable to vary the effective capacity of the capacitor in the control circuit, rather than the actual capacity. An instance of such variation is shown in FIG. 6, which shows a variable inductor 60 shunted directly across capacitor K. Variation in the inductance of this inductor causes variation in the effective capacity in the control circuit, so that adjustment in the output current may be obtained.

It is unnecessary that the capacitor of the control circuit be physically present in the connections to the control coil. As a matter of fact, it will be preferable in many instances to couple the capacitor into the control coil circuit indirectly. FIG. 7 shows such coupling by means of a transformer T, the secondary of the transformer being connected directly across capacitor C, and the primary being connected across control coil L₃. Moreover, the capacitor might be coupled into the circuit through a variable transformer, or Variac, so providing for adjustment of K by variation in transformer turns ratio.

A system for providing transformer coupling of the capacitor into the control coil circuit, while also providing for variation in the effective capacity in the control circuit, is shown in FIG. 8. This system includes a saturable transformer 61 provided with a secondary coil 62 on its center leg. The secondary coil is connected directly across the capacitor. The two outer legs of the transformer are provided with series-connected coils 63 and 64 to which is connected a source of variable D.C. voltage 65. The primary coil of transformer 61 is connected directly across control coil L₃.

As a result of these connections, variation in the value of voltage supplied to the coils 63 and 64 causes variation in the direct current flowing through these coils, and hence of the saturation of the core, thus causing a corresponding change in the primary exciting current and resulting in variation of the effective capacity in the control circuit.

As explained above, all of the embodiments of the invention have a substantially unlimited constancy action

with variation in capacity of the control circuit capacitor. When leakage reactance is ignored, all embodiments described have unlimited constancy. This surprising result is achieved by automatic variation in the mutual inductance of coils on separate legs to compensate for changes in capacity, so that resonance is substantially maintained. As far as is known, the action of transformer systems in accordance with the invention in varying mutual inductance, automatically, without adjustment of parts, is novel.

It will be obvious that many minor variations could be made in the elements of the various embodiments of this invention shown and described without departure from the spirit of the invention. For instance, the positions of the various coils on the respective legs of the transformer core could be changed about and the characteristics fundamental to the system still be maintained. From the description of the various embodiments, it will be evident that all of these embodiments have the following in common:

10 The embodiments include two magnetic circuits, which have two common portions, in one of which common portions the input and output magnetomotive forces aid, and in the other of these two common portions the input and output magnetomotive forces oppose, so that there is no direct coupling between the input and the load. The control magnetomotive force in effect reverses the total or resultant magnetomotive force in its common portion from the direction of the output MMF, so as to couple power from the input to the load through the control electrical circuit. From the above, it will be obvious that this invention is not to be considered limited to the various embodiments shown and described, but rather only by the scope of the appended claims.

What is claimed is:

35 1. A transformer system for supplying power to a load from an A.C. input comprising a four-legged core of ferromagnetic material, said legs being of such configuration and so aligned with each other that substantially closed high permeability paths are formed between all of the legs of the core; at least three coils wound on said core, a first and a second of said coils being wholly wound on a first and a second of said legs, respectively, and connected in series, a third of said coils being wound with each turn thereof encircling both of and only said first and second legs; an input, an output, and a control electrical circuit, all passing current, the input circuit including one of (a) said third coil and (b) the series combination of said first and second coils and being connected across said A.C. input, the output circuit including the other of (a) said third coil and (b) the series combination of said first and second coils and being connected across said load; said input and output electrical circuits forming with said core an input and an output magnetic circuit, one including at least substantial portions of all four of said legs and the other including said first and second legs, said input and output electrical circuits being so inductively related to said first and second legs that the input and output magnetomotive forces generated by the input and output currents aid in one of said first and second legs and oppose in the other of said first and second legs; and a capacitive reactance, said control electrical circuit including said capacitive reactance and being inductively coupled to the leg on which one of said first and second coils is wound; whereby all power coupled between said input and output electrical circuits is immediately coupled through said control electrical circuit, the control current producing a magnetomotive force in said one of said first and second legs is of phase and magnitude to produce a resultant of said control and output magnetomotive forces opposite to the output magnetomotive force in said last-mentioned leg and thereby to couple power from the input to the load through said control electrical circuit and said output electrical circuit.

2. The apparatus of claim 1 in which said control electrical circuit includes said first coil and said capacitive reactance is shunted across said first coil.

3. The apparatus of claim 1 in which said input electrical circuit includes said third coil and said output electrical circuit includes the series combination of said first and second coils.

4. The apparatus of claim 1 in which said input electrical circuit includes the series combination of said first and second coils and said output electrical circuit includes said third coil.

5. The apparatus of claim 1 in which said control electrical circuit includes a control coil wound on the leg on which said one of said first and second coils is wound.

6. The apparatus of claim 5 in which the series combination of said control coil and said capacitive reactance is connected across a source of voltage.

7. The apparatus of claim 6 in which the series combination of said control coil and said capacitive reactance is connected across at least one of said first, second, and third coils.

8. The apparatus of claim 5 in which the series combination of said control coil and said capacitive reactance is connected across one of said first and second coils.

9. The apparatus of claim 5 in which the capacitive reactance is shunted across the control coil.

10. The apparatus of claim 1 in which said control electrical circuit includes a variable inductive reactance shunted across the capacitive reactance to permit variation of the effective capacity and hence of the output current.

11. The apparatus of claim 1 in which said control electrical circuit includes a saturable core transformer, at

least one coil wound on the core of said transformer, a source of D.C. voltage connected to said last-mentioned coil and variable to change the saturation of the transformer core, a secondary coil wound on said transformer core and connected across said capacitive reactance, and a primary coil inductively coupled to said secondary coil.

12. The apparatus of claim 1 in which said control electrical circuit includes a transformer having a primary and a secondary coil, said capacitive reactance being connected across said secondary coil, and said primary coil being inductively coupled to said secondary coil.
